UNITED STATES PATENT OFFICE.

CHARLES E. TREWHELLA, OF FORESTVILLE, CONNECTICUT, ASSIGNOR TO
AMERICAN SILVER COMPANY, OF BRISTOL, CONNECTICUT, A CORPO-
RATION.

PERCOLATOR.

No. 838,224.

Specification of Letters Patent.

Patented Dec. 11, 1906.

Application filed October 10, 1906. Serial No. 338,265.

To all whom it may concern:

Be it known that I, CHARLES E. TREWHELLA, a citizen of the United States, residing at Forestville, in the county of Hartford and State of Connecticut, have invented certain new and useful Improvements in Percolators, of which the following is a specification.

My invention relates to improvements in percolators; and the objects of my improvement are simplicity and economy of construction with efficiency in operation, particularly with reference to the fountain mechanism.

In the accompanying drawings, Figure 1 is a central vertical section of the fountain mechanism and so much of a percolator as is necessary to show its connection therewith, the upper parts being broken away. Fig. 2 is a central vertical section of the sides of the valve-chamber, the top, bottom, valve-stem, 20 and valve being removed.

A designates the lower part of the percolator vessel, the upper part of which (not shown) may be of any ordinary construction. At the bottom of the vessel there is a central depression 3 for a generating-chamber, which chamber is substantially closed at the top by the fountain-base 4, that is seated in the depression 3 in such manner as to leave a space for a generating-chamber 5 between the said 30 base and that portion of the bottom of the vessel which comes within the depression 3. I prefer to form this fountain-base with double walls, so as to form an inclosed air-chamber 6 to serve as a heat-insulator between the generating-chamber and the body of the vessel, all in in well-known manner not peculiar to the invention herein disclosed.

The fountain-base 4 is centrally perforated to receive the cylindrical valve-chamber 7. 40 This chamber is provided with a valve-seat 8, that forms the upper wall of the said chamber and which is provided with a port or ports 9, preferably with three ports. In the center of the valve-seat an ordinary percolator-tube 45 or fountain-tube 10 is secured, the said tube being in communication with the generating-chamber and extended upwardly in the usual manner to the percolating-chamber for conducting the liquid thereto, the upper part of 50 the said tube being shown as broken off. I prefer to provide the valve-chamber 7 with an inner cylinder 11, that extends from the bottom of the valve-chamber upwardly to the valve-seat 8, leaving a space or passage

between the outer and inner cylinders of the 5 valve-chamber. The upper end of the inner cylinder 11 is partially cut away to form openings 12, while openings 13 are formed at the lower end, so that the liquid may flow mainly through the passage between the said two cylinders—that is, between the inner cylinder 11 and the valve-chamber 7, that constitutes the outer cylinder—while the inner cylinder is substantially filled horizontally by a valve, so that but little liquid can 60 pass through the inner cylinder of the valve-chamber. The bottom of the valve-chamber is perforated, as at 14, to make it open downwardly into the generating-chamber and is provided with an upwardly-projecting 70 tubular valve-stem or guide 15, that extends up to the valve-seat and forms the passage through which the fluid flows in its upward movement from the generating-chamber to the fountain-tube 10. The floating valve is 75 mounted to slide loosely on the stem or guide 15. It is composed of a valve-body 16 and outer and inner cylinders 17 and 18, respectively, depending from the said valve-body, so as to form an annular air-chamber underneath the said body. The valve-body is fitted to the valve-seat 8 so as to close the ports 9 when raised. The valve is mainly guided in its sliding up-and-down movements by the valve-stem and inner cylinder 18, while the 80 outer cylinder 17 substantially fills the inner cylinder 11 of the valve-chamber, but is intended to fill the same so loosely that it cannot bind therein. The inner cylinder 18 of the valve is a little longer than the outer cylinder 17, so that when the valve falls to its lowermost position, as shown in Fig. 1, the lower edge of the outer cylinder will not strike the bottom wall of the valve-chamber. The valve 85 may be formed of any suitable material; but I prefer to make it of aluminium on account of the lightness of that material.

The percolator is charged in the ordinary way, the valve at first being down, as shown in Fig. 1. The liquid will flow from the body 100 of the vessel down through the ports 9 in the valve-seat into the valve-chamber and down through said chamber into the generating-chamber. The air within the interior of the valve will be inclosed by the liquid when the valve is submerged, so that the air cannot escape, and thus the valve will float and rise up 105 in the valve-chamber and against the valve-

seat 8 to close the ports 9 therein. Upon subjecting the generating-chamber to heat for a time the fluid therein will be forced up through the valve-stem 15 and fountain-tube 10 in the ordinary manner of analogous percolators. As the fluid is discharged from the generating-chamber and connected valve-chamber sufficiently to let the valve fall and open the parts 9 fresh liquid from above is again admitted, ready to repeat the operation.

It is apparent that some changes from the specific construction herein disclosed may be made, and therefore I do not wish to be understood as limiting myself to the precise form of construction shown and described, but desire the liberty to make such changes in working my invention as may fairly come within the spirit and scope of the same.

20 By my improvement a simple, inexpensive, and compact arrangement of the fountain mechanism is produced. The valve-chamber and valve are centrally arranged and are found to be very sensitive and efficient in action.

I claim as my invention—

1. In a percolator, the combination of a vessel having a generating-chamber at its bottom with a fountain-tube in communication with the said chamber, a valve-chamber opening downwardly into the said generating-chamber, a valve seat and port at the upper end of the said chamber, a valve stem or guide centrally arranged within the said valve-chamber, and a valve mounted to rise and fall on the said valve-stem and having on its under side an annular air-space for lifting

the valve on the said stem when the valve is submerged in liquid.

2. In a percolator, the combination of a vessel having a generating-chamber at its bottom with a fountain-base forming the top of the said chamber, a valve-chamber centrally arranged in the said fountain-base, a valve seat and port at the upper end of the said valve-chamber, a tubular valve stem or guide centrally arranged within the said valve-chamber, a fountain-tube mounted in the said valve-seat in communication with the interior of the said valve-stem, and a valve mounted to rise and fall on the said tubular valve-stem and having an annular air-chamber in its under side.

3. In a percolator, the combination of a vessel having a generating-chamber at its bottom with a fountain-tube in communication with the said chamber, a valve-chamber opening into the said generating-chamber, a valve seat and port at the upper end of the valve-chamber, an inner cylinder inside of the said valve-chamber with a downward passage between the said inner cylinder and main wall of the valve-chamber, a valve stem or guide centrally arranged within the said valve-chamber, and a floating valve mounted on the valve-stem and within the inner cylinder of the said valve-chamber and having a diameter that substantially fills the inner diameter of the said inner cylinder.

CHARLES E. TREWHELLA.
